UNITED STATES PATENT OFFICE.

EARL M. BUNCE, OF FENTON, MICHIGAN.

APPARATUS FOR BURNING FUEL IN FURNACES.

No. 906,194.

Specification of Letters Patent.

Patented Dec. 8, 1908.

Application filed January 26, 1907. Serial No. 354,253.

To all whom it may concern:

Be it known that I, EARL M. BUNCE, a citizen of the United States, residing at Fenton, in the county of Genesee and State of Michigan, have invented new and useful Improvements in Apparatus for Burning Fuel in Furnaces, of which the following is a specification.

The object of my invention is the provision of apparatus or means for burning fine fuel in suspension, such as pulverized coal, when mixed with air, in a furnace, and especially in rotary kilns, whereby relatively complete combustion may be secured by thoroughly mixing the fuel with the air, and whereby when the apparatus is used in connection with a rotary or other kiln for burning Portland cement clinker the intensity of the flame or heat may be localized at various points or places inwardly from the extreme lower end of the kiln, and said flame also may be directed towards any portion of the internal surface of the kiln as well as axially thereof.

The invention consists in certain novelties of construction and combinations of parts hereinafter set forth and claimed.

The accompanying drawings illustrate one example of the physical embodiment of the invention constructed and arranged according to the best of the several modes I have so far devised for the practical application of the principle.

Figure 1 is a side view in elevation of the apparatus showing its use in connection with a rotary kiln. Fig. 2 is a top plan view of Fig. 1. Fig. 3 is an enlarged end view. Fig. 4 shows by a view in perspective the means for adjusting the pipes horizontally. Fig. 5 shows by a view in perspective part of the toggle lever mechanism for adjusting a pipe vertically.

Referring to the several figures, the numeral 1 designates the lower portion or end of a rotary kiln which may be of any well known construction and be supported and revolved in any suitable way well known in the art; 2, a housing or hood of a well known type supported upon wheels and having an opening upon one vertical side which in this instance receives or matches the tubular end of the rotary kiln; 3, two castings set in the wall of the hood and extending through the fire brick, indicated by dotted lines, each casting being a hollow truncated cone in shape and the axial lines of the two cones

disposed at an angle to each other; 4, fuel discharge pipes with their ends located within and slightly projecting beyond the smaller ends of the truncated cones, thus forming 60 swivel connections with said cones; 5, retaining bands or rings upon the ends of the pipes for preventing their withdrawal from the cones; 6, the main blast pipe connected with a blower and source of fuel supply; 7, 7, 65 the two branches leading from the main blast pipe; 8, sections of pipe constituting continuations of the branches to the fuel discharge pipes; 9, flexible hose connecting the several pipes whereby three universal 70 joints are provided between each branch of the main pipe and the fuel discharge pipe; 10, rods for supporting the end of the main pipe and the several branch pipes; 11, a damper located within the main pipe at its 75 junction with the branches; 12, the shaft; 13, a perforated lever arm; 14, a slotted semi-circular bearing supported by the main pipe; 15, a bolt passed through the slot in the circle and the end of the lever; 16, a 80 winged nut on the bolt; 17, a channel iron section at the rear top edge of the hood occupying a horizontal position; 18, a channel iron secured at the front top edge of the hood; 19, two channel irons secured to the 85 ends of channels 17 and 18 and with their free ends extended rearwardly a suitable distance from the hood; 20, a horizontally disposed Z-bar located below the truncated cones; 21, a bent strap secured to the Z-bar; 90 22, two metallic bars spaced apart and with their front ends secured to the strap 21 in any way; 23, two obliquely disposed angle irons extending from the ends of the channels 19 to the ends of the bars 22, and which 95 support the ends of said bars; 24, a threaded shaft with a hand wheel; 25, a perforated block which supports the hand wheel end of the shaft and within which the shaft is loosely journaled; 26, a fixed block having a 100 bearing for the end of the shaft and within which the end of the shaft turns; 27, a movable block with a threaded hole for the reception of the threaded portion of the shaft; 28, two toggle levers; 29, a journal by which 105 the meeting ends of the levers are pivoted to the movable block; 30, pivotal joints which connect the ends of the levers with the universal joints at the ends of the fuel discharge pipes; 31, toggle levers pivoted at their 110 meeting ends upon a bolt 32 which is provided with a winged nut 33, as shown; 34,

an operating handle pivoted upon the bolt 32 at the meeting ends of the levers; 35, the pivotal joints which unite the outer levers to the channel bars 19 in any suitable way; 5 and 36, the pivotal joints which unite the lower levers to the universal joints or connections at the ends of the fuel discharge pipes.

Any suitable type of blower and means for 10 supplying fine fuel, such as pulverized coal, to the main blast pipe 6 may be employed and such blowers and means being well known in the art I have not illustrated or described the same.

15 The mode of operation is as follows: Assuming the fuel discharge pipes 4, 4, to be in the relative positions shown by Fig. 2 and powdered fuel mixed with air to be projected from the discharge pipes, the two currents or streams will meet at point or place A where the fuel and air will become thoroughly commingled and the two currents change directions and become united to form 20 a single current extending in a substantially straight line B—B, when the fuel and air issue from the discharge pipes under like pressure. The fuel being ignited an intense heat is localized at the place A and for some distance inwardly therefrom, the length of 25 the flame depending upon the amount of fuel discharged and the air pressure. By turning the damper 11 in the main blast pipe 6 so that more fuel and air under pressure will be delivered from one of the discharge 30 pipes than from the other, the flame will be shifted from the place A to a position at one side of a vertical plane passing through the lines B—B. Obviously the flame can thus be shifted from side to side of the internal 35 surface of the kiln as occasion may demand. To change the place A of the most intense heat to a position nearer the lower end of the kiln, as at C, the threaded shaft 24 is 40 revolved, the toggle levers 28, 28 operated, and the discharge pipes 4, 4, moved apart at their free ends so the air and fuel delivered 45 will meet at the place C.

To localize the flame and most intense heat inwardly at any place on the line B—B 50 from the lower end of the kiln the free ends of the discharge pipes 4, 4, are moved towards each other by the toggle lever mechanism and the currents or streams of air and fuel thus caused to meet at the desired place. 55 When the discharge pipes 4, 4, coincide in direction with the lines D—D the place of most intense heat will be located far within the kiln at the meeting point or place of the two streams or currents of air and fuel. As 60 previously explained in connection with the place A, the flame may be shifted from side to side of the internal surface of the kiln from the point or place wherever in the plane of the line B—B the two currents of

fuel and air may be caused to unite or meet. 65 By the manipulation of the toggle levers 31, 31, the free ends of the discharge pipes may be moved so that the common flame will be localized at the top internal surface or bottom internal surface of the kiln, near 70 the lower end of the kiln, as indicated by the dotted lines E and F, or it may be localized at the top and bottom internal surfaces at places some distance within the kiln.

It will be observed that each discharge 75 pipe 4 forms at one end with the surface bounding the smaller opening in a truncated cone casting a swivel joint, or universal joint, and that the opposite end can be moved through practically the circumference of a circle so that the current of fuel and air may be directed towards any portion of the internal surface of the kiln or axially thereof. Under some conditions it may be desirable to use a single discharge pipe thus 80 swiveled at one end in the wall of the hood, but two such pipes are preferably employed and the currents of fuel and air or flames united to form one current or flame inasmuch as by bringing the currents of fuel 85 and air together the same are more thoroughly mixed and more complete combustion with a greater heat results. Again, by bringing the two flames or currents of air and fuel together at an angle the heat may 90 be localized near the lower end of the kiln and in this and other locations there is less tendency for the flame and heat to swiftly pass through the kiln to the stack before the heat has been transmitted to the material 95 under treatment.

The advantages secured by the use of my improved apparatus in connection with burning raw materials into Portland cement clinker are obvious. With devices now in 100 use the length of the clinkering zone is very limited and the raw material frequently passes the zone without being thoroughly burned, under which circumstances the kiln must be stopped and the unburned material 105 driven back. By the use of my apparatus the clinkering zone can be brought to the lower end of the kiln or the heat elsewhere localized and the flame directed upon the material not thoroughly burned. In fact 110 the point or zone of clinkering is under the control of the operator at all times. Furthermore, the formation of "rings" may be prevented or the same readily burned off 115 when formed as the flame can be directed to any point within the lower portion of the kiln and the heat there intensified.

From the foregoing description taken in connection with the drawings, it is clear that I have produced an apparatus whereby a 120 plurality of streams of fuel and air are united and thoroughly commingled and more perfect combustion secured when the said 125

streams of fuel and air are ignited, and whereby the resultant flame may be moved from place to place within a furnace or rotary kiln and the heat localized for any desired purpose.

While I have shown and described only one example of the apparatus or means whereby the principle is physically embodied I do not intend to limit the scope of the invention to such specific means, as equivalent means may be employed to perform the same or analogous functions, for instance, the fuel discharge pipes may be bodily movable at the ends in lieu of having swiveled or universal joint connections with the two truncated cones, a different type of flexible joint be selected, other means be used to move the discharge pipes simultaneously or successively, and two main supply or blast pipes each having a damper be substituted for the main blast pipe with branches as herein illustrated.

What I claim is:

1. The combination with a furnace, of a discharge pipe swiveled or universally jointed at its front end in the wall of the furnace and bodily movable at the rear end to positions within the arc of a circle, and means embracing a pipe universally jointed to the rear end of the discharge pipe for delivering air and fuel to said discharge pipe.

2. The combination with a furnace, of a discharge pipe swiveled or universally jointed at its front end and movable at the rear end; means for moving said pipe; and means embracing a pipe universally jointed at one end to the rear end of the discharge pipe for delivering fuel and air through said pipe to the furnace.

3. The combination with a furnace, of means for delivering two streams of air and fuel into the furnace so they will meet, change their directions, become thoroughly commingled and form practically one stream; and means for changing the meeting point or place of the two streams within the furnace.

4. The combination with a rotary kiln, of means for delivering a plurality of streams of commingled air and fuel against each or one another so as to form practically one stream; and means for localizing the stream so formed at different places within the interior of the kiln.

5. The combination with a rotary kiln, of means for delivering two streams of air and fuel into the kiln so they will unite and form practically one stream; and means for forcing the said stream to one side of the meeting place of the said two streams of air and fuel.

6. The combination with a furnace, of two movable fuel discharge pipes, means for supplying fuel and air to the pipes and means

for supporting them in different positions so that the air and fuel discharged therefrom may be caused to successively meet at an angle at a plurality of points or places within the furnace.

7. The combination with a furnace, of two movable fuel discharge pipes; means for supplying fuel and air to the pipes; means for angularly supporting the pipes; and means for adjusting the said pipes to different angular positions in a horizontal plane so that the two streams of air and fuel may be caused to meet at different points or places within the furnace.

8. The combination with a furnace, of two fuel discharge pipes angularly disposed each to the other; means for supporting the same; means for supplying fuel and air to the pipes; and means for adjusting the pipes vertically so the flame may be directed upwardly or downwardly within the furnace.

9. The combination with a furnace, of two fuel discharge pipes; means for supplying fuel and air to the pipes; and means for adjusting the pipes both vertically and horizontally so the two streams of fuel and air delivered from the pipes will meet at a plurality of points or places within the furnace and form one stream.

10. The combination with a kiln, of two fuel discharge pipes each swiveled at one end and movable at the other end; means for adjusting the pipes to angular positions; and means for supplying fuel and air to the same.

11. The combination with a kiln, of two fuel discharge pipes angularly disposed each to the other so the streams of fuel and air will meet to form one stream; means for supplying fuel and air to the pipes; and means for delivering more fuel to one of the pipes than to the other, for the purpose set forth.

12. The combination with a kiln, of two fuel discharge pipes angularly disposed each to the other so the streams of air and fuel will meet, change their directions, become thoroughly commingled, and form one stream; and means for adjusting the pipes to different angular positions, for the purpose set forth.

13. The combination with a rotary kiln, of two movable fuel discharge pipes angularly disposed each to the other so the streams of air and fuel will unite, change their directions, become thoroughly commingled, and form one stream; and means for adjusting the said pipes and holding them in relative adjusted positions.

14. The combination with a rotary kiln, of two movable fuel discharge pipes angularly disposed each to the other so the streams of fuel discharged will be united to form one stream; fuel supply pipes joined

- to the discharge pipes and to a main supply pipe by flexible joints; and means for adjusting the discharge pipes.
15. The combination with a rotary kiln of two movable fuel discharge pipes angularly disposed each to the other; fuel supply pipes each flexibly jointed to a discharge pipe at one end and to another supply pipe at the opposite end; and means for adjusting the discharge pipes.
16. The combination with a rotary kiln, of two movable fuel supply pipes angularly disposed each to the other so the streams of fuel and air discharged will unite, change their directions, become thoroughly commingled, and form one stream; means for supplying fuel and air; and toggle lever mechanism for horizontally adjusting said pipes to different angular positions.
17. The combination with a rotary kiln, of two movable fuel supply pipes angularly disposed each to the other so the streams of fuel and air discharged will unite, change their directions, become thoroughly commingled, and form one stream; means for
- supplying fuel and air; and toggle lever mechanism for vertically adjusting said pipes to different positions.
18. The combination with a rotary kiln, of two fuel discharge pipes each swiveled at one end in the wall of a hood or housing and flexibly united at the opposite end to a fuel delivery pipe; means for supplying air and fuel to the pipes; and means for moving the discharge pipes to different angular positions.
19. The combination with a rotary kiln, of two fuel discharge pipes each swiveled at one end in the wall of a hood or housing and flexibly united at the opposite end to a movable fuel delivery pipe; means for supplying air and fuel to the pipes; and means for moving the discharge pipes to different angular positions.

In testimony whereof I affix my signature in presence of two witnesses.

EARL M. BUNCE.
